UNITED STATES PATENT OFFICE.

EDWARD H. McCLOUD, OF COLUMBUS, OHIO, ASSIGNOR TO THE KINNEAR MANUFACTURING COMPANY, OF COLUMBUS, OHIO, A CORPORATION OF WEST VIRGINIA.

DOOR.

1,285,284.

Specification of Letters Patent. Patented Nov. 19, 1918.

Application filed March 1, 1916. Serial No. 81,526.

To all whom it may concern:

Be it known that I, EDWARD H. McCLOUD, a citizen of the United States, residing at Columbus, in the county of Franklin and 5 State of Ohio, have invented a certain new and useful Improvement in Doors, of which the following is a specification.

This invention relates to the type of door that includes two sections, one of which is 10 slid up in front of the other, the two sections being then tilted together from the door opening to horizontal position; and the object of the invention is to provide a simplified and improved construction of this 15 type whereby its operation is made easier and more efficient.

This invention is embodied in the example shown in the accompanying drawings, set forth in the following description and 20 finally claimed.

In said drawings—

Figure 1 is a view in elevation looking at what is ordinarily the inner side.

Fig. 2 is a vertical section on the line 25 III—III, Fig. 1 looking to the left.

Fig. 3 is a horizontal section on the line I—I, Fig. 1, on a larger scale.

Fig. 4 is a similar section on the line II—II, Fig. 1.

30 In the views 5, 5 designates vertical channels which are to be suitably secured to the vertical portions of the doorway casing. 6 designates the lower door section and 7 the upper section. The lower corners of the 35 lower section 6 are each provided with rollers 8 journaled in brackets 9; and connected with said brackets are chains or cords passing upward over suitable pulleys 10 and 11 to a counterbalancing weight 12. The upper 40 corners of the lower section are each also provided with a flanged roller or wheel 13 for the purpose to be hereinafter referred to.

The upper section 7 in its vertical position 45 is supported by means of small rollers 14 journaled on bearings projecting laterally from the upper corners of that section, said rollers resting on short track portions 15 on brackets designated generally as 16. The 50 vertical edges of the upper section are provided with angle bars 17 having one web offset from the face of the section so as to form channels in which the vertical edges of the lower section travel when that section

is raised. When the lower section is raised 55 to the position where it coincides horizontally or is opposite the upper section the latter section is engaged by hooks 18 fixed to the lower portion of the lower section so that the two sections are coupled for further movement together in the same direction.

The brackets 16 are provided with curved grooves 19 that are engaged by the central or projecting portions of the wheels 13; and the lower rim of said groove is extended horizontally as a track 20 upon which the wheels 13 ride to support the upper portions of the two sections after said wheels leave the grooves.

The upper section 7 is provided at each of its upper corners with a latch pivoted at 21, said latch having an arm 22 to engage a shoulder 23 on the bracket 16 when the upper section 7 is in vertical position and 75 a dependent arm 24 having a downwardly and outwardly inclined end 25. When the lower section is raised the bearings of the rollers 13 strike the inclined ends 25 and raise the latching arm 22 thereby releasing 80 the upper section permitting it to be deflected outward from the wall with the lower section, the lower section being directly deflected by the engagement of the rollers 13 with the curved grooves 19. The 85 upper wall of the grooves 19 thus causes initial outward deflection of the upper portions of the coupled sections but after some considerable deflection the rollers 13 ride on the tracks which support the sections at 90 those portions, while the lower portions are supported by the chains or cords as indicated by broken lines Fig. 2. By raising the lower portions of the sections sufficiently the sections can be brought to substantially 95 horizontal position. To permit the deflection of the sections at the upper portions of the channels the latter at those portions are cut away and made narrower as seen at 5^a.

The character 26 designates an endless chain running over a sprocket wheel 27, the shaft of which has a spur gear 28 to engage a spur gear 29 on the shaft of the pulley 11. By these or other familiar means the door, 105 when heavy, can be conveniently opened and closed. To close the door the operation is merely reversed. When the coupled doors

first reach the vertical position the latch drops to latching position after which the lower section descends by gravity or otherwise as may be desired to close the lower portion of the opening.

What I claim is:

1. A door including, in combination, an upper and a lower section, means for raising the lower section into coincidence with the upper section, means engaging the sections with each other, a track upon which the upper section is hung and is movable face-wise from the door opening, deflecting means, and means on the lower section for engaging said deflecting means, and a second track to support the upper ends of the combined sections when deflected.

2. A door including, in combination, an upper and a lower section, means connected with the lower end of the lower section for raising that section into coincidence with the upper section, means engaging the sections with each other, a track upon which the upper section is hung and is movable face-wise from the door opening, deflecting means, and means on the lower section for engaging said deflecting means, and a second track to support the upper ends of the combined sections when deflected.

3. A door including, in combination, an upper section and a lower section, means for counterbalancing and raising the lower section into coincidence with the upper section, means engaging the sections with each other, a track upon which the upper section is hung and is movable face-wise from the door opening, deflecting means, means on the lower section for engaging said deflecting means, and a second track to support the upper ends of the combined sections when deflected.

per ends of the combined sections when deflected.

4. A door including, in combination, an upper section and a lower section, means connected with the lower end of the lower section for counterbalancing and raising that section into coincidence with the upper section, means engaging the sections with each other, a track upon which the upper section is hung and is movable face-wise, deflecting means, means on the lower section for engaging said deflecting means, and a second track to support the upper ends of the combined sections when deflected.

5. A door including, in combination, an upper and a lower section, means connected with the lower end of the lower section for raising that section into coincidence with the upper section, means engaging the sections with each other, means upon which the upper section is supported and travels so as to be movable face-wise from the door opening, deflecting means, and a separate support to carry the load of the upper end of the upper section after the deflection of the combined sections.

6. A door including, in combination, an upper and a lower section, means connected with the lower end of the lower section for raising that section into coincidence with the upper section, means engaging the sections with each other, means upon which the upper section is supported and travels so as to be movable face-wise from the door opening, deflecting means acting directly on the lower section, and a separate support to carry the load of the upper end of the upper section after the deflection of the combined sections.

EDWARD H. McCLOUD.
